(57) **CLAIM**

I claim the ornamental design for a trash can for vehicle, as shown and described.

DESCRIPTION

FIG. 1 is a top, front perspective view of a trash can for vehicle, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, rear perspective view thereof.

The broken lines in the drawings depicting a strap at a rear side of the trash can for vehicle do not form a part of the claimed design. All other broken lines in the Figures are used to illustrate stitching in the claimed design.
